UNITED STATES PATENT OFFICE.

WILLIAM W. BALDWIN, OF CLEVELAND, OHIO, ASSIGNOR TO THE CLEVELAND CO-OPERATIVE STOVE AND HOLLOW WARE FOUNDRY COMPANY, OF SAME PLACE.

DESIGN FOR A SHEET-METAL STOVE.

SPECIFICATION forming part of Design No. 27,506, dated August 10, 1897.

Application filed June 4, 1897. Serial No. 639,479. Term of patent 7 years.

To all whom it may concern:

Be it known that I, WILLIAM W. BALDWIN, a citizen of the United States, residing at Cleveland, in the county of Cuyahoga and State of Ohio, have invented and produced a new, useful, and original Design for Sheet-Metal Stoves, of which the following is a full, clear, and exact description, reference being had to the accompanying drawing, forming a part thereof.

The drawing is a perspective view of a stove made in accordance with my design.

The leading feature of my design consists of a sheet or plate metal box rectangular in horizontal section and an approximately lyre shape in vertical section, the sides of which are without ornamentation and are smooth except for the ridges at the upright edges where the ends overlap. On one of the ends of the box is a spout or chute of a generally semicylindrical form, but having its lower end tapered to join the box. This spout, how-

ever, is not deemed an essential feature of the design. The stove stands on four legs and has a flanged top, over a considerable portion of which there is a cover. It also has a flanged hole for the pipe, as usual.

Referring to the parts by letters, A represents a side of the stove, and B one of the approximately lyre-shaped ends.

C represents the spout, and c its conical tapered end. The four legs of the stove are shown at D, the top at E, the cover at F, and the pipe-hole flange at G.

I claim—

The design for a stove, substantially as shown and described.

In testimony whereof I affix my signature in presence of two witnesses.

WILLIAM W. BALDWIN.
